US0D1076802S

(12) **United States Design Patent** (10) **Patent No.:** **US D1,076,802 S**
(45) **Date of Patent:** **** May 27, 2025**

(54) **PORTABLE POWER BANK**

(71) Applicant: **Shenzhen Autral Technology Innovation Co., Ltd.**, Shenzhen (CN)

(72) Inventor: **Minmin Zhang**, Shenzhen (CN)

(73) Assignee: **SHENZHEN AUTRAL TECHNOLOGY INNOVATION CO., LTD.**, Shenzhen (CN)

(**) Term: **15 Years**

(21) Appl. No.: **29/907,068**

(22) Filed: **Jan. 4, 2024**

(51) LOC (15) Cl. **13-02**

(52) U.S. Cl.

USPC **D13/108**

(57) **CLAIM**

The ornamental design for a portable power bank as shown and described.

DESCRIPTION

FIG. 1 is a front perspective view of a portable power bank showing our new design;

FIG. 2 is a rear perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the Figures are for the purpose of illustrating portions of the portable power bank that form no part of the claimed design.

1 Claim, 8 Drawing Sheets
